UNITED STATES PATENT OFFICE.

WILLIAM H. C. HIGGINS, JR., OF LAPORTE, INDIANA, ASSIGNOR TO M. RUMELY
COMPANY, OF LAPORTE, INDIANA, A CORPORATION OF INDIANA.

CARBURETER.

1,157,368.

Specification of Letters Patent. Patented Oct. 26, 1915.

Application filed March 8, 1913. Serial No. 752,966.

To all whom it may concern:

Be it known that I, WILLIAM H. C. Higgins, Jr., a citizen of the United States, residing at Laporte, in the county of Laporte, and State of Indiana, have invented a certain new and useful Improvement in Carbureters, of which the following is a specification.

My invention relates to improvements in carbureters particularly those carbureters which are designed for use in the burning of the heavier, less volatile and less easily carbureted fuels such as kerosene, distillate and the like.

15 It is illustrated diagrammatically in one form in the accompanying drawings where-

in—
Figure 1 is a side elevation showing the carbureter and air supply with parts in section and parts broken away; Fig. 2 is an end elevation with parts broken away; Fig. 3 is a vertical section along line 3—3 of Fig. 5; Fig. 4 is a section along line 4—4 of Fig. 3; Fig. 5 is a horizontal section through the carbureter along the line 5—5 of Fig. 3; Fig. 6 is a section along line 6—6 of Fig. 5.

Like parts are indicated by like letters in all of the several figures.

The manifold A has two branches A¹, A² which lead respectively to the two cylinders of the engine which for the sake of clearness is not here shown, although it might be any type of combustion engine. The flanges A³ are provided for convenience in attaching the manifold and in supporting it from the engine cylinders. The air chamber A⁴ is attached to the manifold by the cap screws A⁵, is open at the top and has projecting therefrom an elbow A⁶ which is connected to the air supply pipe A⁷. This air supply pipe A⁷ has two branches; one A⁸ leads to a hot air jacket A⁹ around the exhaust pipe A¹⁰, and the other A¹¹ draws cool air from the atmosphere. The shutter valve A¹² is pivoted in the supply pipe A⁷ and adapted by its position to vary the relative amount of hot or cold air drawn in. The butterfly valve A¹³ is located in the pipe A⁷ between the two branches and the elbow A⁶ and is adapted to be operated at the will of the operator to increase the draft and assist in starting.

The carbureter B itself is mounted on the manifold and the air chamber A⁴ closing the open top of the air chamber A⁴, and the opening B¹ leading through the wall of the

manifold into the interior thereof. The cap screws B² hold the carbureter in position. A valve seat B³ rests upon the top of the manifold and the top of the air chamber, and the sliding valve B⁴ slides upon that seat being guided thereupon by the shoulders B⁵ on the inner wall of the carbureter. The carbureter consists of a suction or vacuum carbureting or mixing chamber B⁶ having at its bottom this slide valve B⁴. 65 This slide valve B⁴ is provided with an aperture B⁸ therethrough so that air may be drawn through the supply pipe to the aperture B⁸ into the vacuum chamber B⁶ and thence through the port B¹ into the manifold. A connecting rod B⁹ and link B¹⁰ leads to the control by a connection not shown so that the carbureter may be controlled in response to the conditions of the engine, or if desired this connection may 75 lead to a manually operated device. It will be noted that the aperture B⁸ in the slide valve B⁴ is in register with the opening B¹¹ leading from the air chamber A⁴ into the carbureting chamber B⁶ and when the valve 80 is in the position shown in Fig. 3 the air passes the opening B¹¹ and the opening B⁸. When, however, the valve is withdrawn it will tend to bring the opening B⁸ partially 85 at least out of register with the openings B¹¹ and permit air to pass in around the end of the valve B⁴. The shutter B¹² is adjustable across the opening B¹¹ so as to change the relative areas of the discharge left through the openings B¹¹ and B⁸ and 90 through B¹¹ around the end of the valve. Thus, as the valve is drawn to the left the opening B¹¹ will be closed by the end of the valve, the opening B⁸ will be closed and the opening around the end of the valve will be 95 open. The parts preferably will be arranged so that this will result in a decrease both of the discharge opening into the manifold and the suction opening leading from the air chamber into the suction or carbureting chamber. The relation might be anything that experience showed to be desirable although under ordinary circumstances it will be found that as the opening leading into the manifold decreases it would be necessary to decrease the intake opening less rapidly since with a decreased amount of air it would probably be desirable to supply a decreased amount of liquid fuel and this may be done only by decreasing the vacuum. 100 105 110

If while the discharge port decreases it still increases with respect to the intake port this situation would prevail, that is to say, the vacuum or suction would be decreased and 5 a suitable mixture would still be supplied. This, of course, is not positive and under some circumstances it might be desirable to change the relations. In fact, experience shows that for every engine and every type 10 it is necessary to change the relations and therefore this discussion is merely for the purpose of illustration.

The oil and water supply chambers C C¹ are kept supplied with oil and water from 15 any suitable source of supply through the pipes C² C³. The liquid floods the chambers up to the levels of the wells C⁴ C⁵ and then discharges through the overflow C⁶ C⁷ to 20 the main reservoirs. The liquid from these two chambers is fed through the supply nozzles C⁸ made up of the inner sleeve C⁹ and outer sleeve C¹⁰ and the screen C¹¹. A 25 passage C¹² through the sleeve C¹⁰ permits access of the material which passes through the screen to the interior of the sleeve C¹⁰. A 30 passage C¹³ permits the liquid from the interior of the cylinder C¹⁰ to enter the interior of the cylinder C⁹ whence it passes down into the opening C¹⁴ through the fuel 35 nozzle C¹⁵ being controlled in its passage by the needle valve C¹⁶. In practice it is necessary to manipulate these valves to suit conditions although practice shows that once they have been adjusted they may always be 40 returned to the same adjustment for the same engine.

The chamber D is provided for the purpose of priming the engine with gasoline. This discharges into the interior of the carbureting chamber through the valve which 45 is made up of a sleeve or pipe D¹ and provided with a solid jacket D² extending down to a point adjacent the bottom of the tank. The ports D³ lead through the sleeve or 50 pipe D¹ from the top of the chamber formed between it and the jacket into the interior. The needle valve D⁴ controls the passage of the material to the parts D⁵ into the pipe whence it passes down through the wire 55 strainer D⁶ to the interior of the carbureting chamber.

For the purpose of filling the priming chamber with gasoline and for generally priming the carbureter manifold a pipe E 60 is provided which leads from a suitable source of gasoline or other highly volatile combustible fuel not shown through a ball check valve E¹ into a vertical passage or chamber E². This chamber or passage communicates with the horizontal passage E³ which discharges into a pump barrel E⁴ into which reciprocates a pump plunger E⁵. The 65 passage E² also communicates through the ball check valve E⁷ with the passage E⁸ which passage is in communication through

the passage E⁹ past the ball valve E¹⁰ with the passage E¹¹ leading to and discharging into the priming chamber D. The spring E¹² tends normally to keep the ball valve closed on its seat and resist the discharge of 70 the liquid into the priming chamber.

The passage F leads from the passage E⁸ to the passage F¹ being controlled by the petcock F² manipulated by the handle F³ which when in the position shown in Fig. 2 75 leaves the passage open and when at right angles thereto would close the passage and compel all the liquid to pass through the passage E⁹ against the ball valve E¹⁰. The pipe F¹ leads down through the wall of the 80 manifold to the spray head F⁶. This spray head is provided with three spray apertures, one F⁶, discharging upwardly toward and into the carbureter, the other two, F⁴, discharging horizontally toward and through 85 the end of the manifold. It will be evident that when the valve F³ is in the position shown in Fig. 2 and the pump is manipulated on each upward stroke of the pump gasoline will be drawn into the pump, and 90 on the downward stroke will be expelled through the pipe F¹ and spray head F⁶ some of the material being violently projected into the carbureter. Thus a few 95 strokes of the piston will fill the carbureter manifold and all connections with finely divided gasoline preparing a satisfactory starting mixture. The valve will then be at right angles to the position shown in Fig. 2 and if the pumping movement has continued the priming chamber will be filled with gasoline ready to run the engine for its 100 initial start.

The cup G supported on the bottom of the manifold by the cap screw G¹ is provided 105 about its sides with the openings G² and contains the padding or wick G³ and has the openings G⁴ along its upper edge. For the purpose of heating the manifold preferably kerosene or gasoline is squirted into 110 this cup to saturate the wick. Gasoline makes a quick flame without smoke and is therefore preferably used. It heats the manifold so as to prevent precipitation of 115 the gasoline in starting and so as to facilitate starting of the engine.

It will be evident that, while I have shown in my drawings an operative device, still many changes might be made in size, shape and arrangement of parts without departing materially from the spirit of my invention, and I wish, therefore, that my drawings be regarded as in a sense dia- 120 grammatic.

The use and operation of my invention are 125 as follows: The operator will first place the starting valve in the position shown in Fig. 2. He will then make a few strokes of the pump until gasoline has been sprayed into the manifold and until the manifold and car- 130

bureter have both been filled with a satisfactory supply of gasolene to mix with the air and form a combustible mixture. The carbureter itself will on the action of the 5 pump be filled with the spray so that when at a later time the engine is turned over to suck gasolene from the carbureter there will be no break in the supply of fuel and at either suction stroke the piston will draw 10 into the cylinder carbureted air. Meanwhile, the cup beneath the manifold will have been filled with gasolene and allowed to heat the manifold and to a certain extent the carbureter to prevent precipitation of 15 the finely divided gasolene which, however volatile, is likely to be precipitated at very low temperature. With the manifold full of the carbureted mixture the operator will move the handle to the position marked 1 20 and continue pumping until he fills the priming chamber. He will turn off the oil and water valves and turn off the butterfly valve A^{13} to substantially close the air intake. He will then start the engine in the usual manner 25 the first stroke drawing the finely divided gasolene and air mixture to the engine. When the first charge is fired the engine will then start drawing up first the gasolene mixture from the manifold and carbureting 30 chamber and subsequently from the gasolene priming reservoir through the carbureting chamber and manifold without break or interruption of the carbureted mixture. As soon as the engine takes hold the operator 35 will open the valve A^{13} and permit air to flow freely through the intake pipe. Depending on conditions he will manipulate the shutter A^{12} to control the relative proportions of hot and cold air. It may be 40 necessary to have it hot or cold as the case may be or any mixture between these two limitations. This experience will show. The engine will then run on gasolene only for a short period, a few minutes only being 45 necessary in coldest weather. Experience shows that these engines will heat up even in zero weather on less than a pint of gasolene of such temperature that kerosene and water may then be turned on and the engine 50 run exclusively on kerosene and water after gasolene in the priming chamber has been exhausted.

Experience shows that when combustion

engines are to be started in cold weather it is frequently desirable to prime the cylinders with liquid gasolene but experience also shows that when this is done and the engine is started the gasolene in the cylinder will be sufficient to explode on one stroke but as the engine turns over cold uncarbureted air will 55 be drawn from the manifold and carbureter into the cylinder and the impulse of one explosion will frequently not be sufficient to carry the engine over far enough to start the carbureted air since it is necessary first to 60 scavenge the carbureter of uncarbureted air. In order to prevent this I provide means for flooding the carbureter and manifold with a mixture so that from the very first suction stroke the engine draws a combustible mixture 65 from the carbureter and manifold and there is no break in the column of combustible mixture.

It will be obvious that the above invention might be applied to any type of engine of 70 one or more cylinders although for the sake of convenience I have applied it to a two cylinder engine.

I claim:

1. A carbureter comprising a carbureting 75 chamber, liquid reservoirs discharging thereinto, a manifold through which the carbureter discharges, a pump and means for controlling it to inject liquid fuel in a finely divided condition into the manifold and carbureting chamber and means for controlling 80 it to pump liquid into one of said liquid reservoirs.

2. A carbureter comprising a carbureting 85 chamber, liquid reservoirs discharging thereinto, a manifold through which the carbureter discharges, a pump and means for controlling it to inject liquid fuel in a finely divided condition into the manifold and carbureting chamber, means for controlling it 90 to pump liquid into one of said liquid reservoirs, and a housing containing said pump, reservoirs and carbureting chamber all in fixed relation each to the other.

In testimony whereof, I affix my signature 95 in the presence of two witnesses this 20th day of February, 1913.
